(57) **CLAIM**

The ornamental design for an electronic device, as shown and described.

DESCRIPTION

FIG. 1 is a right side view of an electronic device showing my new design in a closed configuration, shown in a first embodiment;

FIG. 2 is a front view thereof;

FIG. 3 is a bottom view thereof;

FIG. 4 is a left side view thereof;

FIG. 5 is a back view thereof;

FIG. 6 is a top view thereof;

FIG. 7 is a front view of the electronic device thereof shown in an open configuration;

FIG. 8 is a bottom view thereof;

FIG. 9 is a bottom, front perspective view of the electronic device thereof, shown in an environment of use;

FIG. 10 is a right side view of the electronic device shown in a second embodiment;

FIG. 11 is a front view thereof;

FIG. 12 is a bottom view thereof;

FIG. 13 is a left side view thereof;

FIG. 14 is a back view thereof;

FIG. 15 is a top view thereof;

FIG. 16 is a front view of the electronic device thereof shown in an open configuration;

FIG. 17 is a bottom view thereof; and

FIG. 18 is a bottom, front perspective view of the electronic device thereof, shown in an environment of use.

The broken line showing of the earphones in FIGS. 9 and 18

(Continued)

depict environment and forms no part of the claimed design. All other broken lines depict portions of the electronic device that form no part of the claimed design.
